UNITED STATES PATENT OFFICE

HARRIET M. TRENHOLM, OF WALTHAM, MASSACHUSETTS

DESIGN FOR A BRACELET OR SIMILAR ARTICLE

Application filed January 29, 1932. Serial No. 42,668. Term of patent 7 years.

To all whom it may concern:

Be it known that I, HARRIET M. TRENHOLM, a citizen of the United States, residing at Waltham, county of Middlesex, Commonwealth of Massachusetts, have invented a new, original, and ornamental Design for a Bracelet or Similar Article, of which the following is a specification, reference being had to the accompanying drawings, forming a part thereof.

In the drawings:

Fig. 1 is a plan view of a bracelet or similar article showing my new design, and

Fig. 2 is a front elevational view of the same.

I claim:

The ornamental design for a bracelet or similar article substantially as shown.

HARRIET M. TRENHOLM.
